Primary Examiner — Austin Murphy

(74) Attorney, Agent, or Firm — KPPB LLP

(57) **CLAIM**

The ornamental design for a media plug adapter, as shown and described.

DESCRIPTION

FIG. 1 is a top view of a media plug adapter, according to an embodiment of the invention.

FIG. 2 is bottom view of the embodiment of FIG. 1.

FIG. 3 is a first side view of the embodiment of FIG. 1.

FIG. 4 is a second side view of the embodiment of FIG. 1.

FIG. 5 is a first end view of the embodiment of FIG. 1.

FIG. 6 is a second end view of the embodiment of FIG. 1.

FIG. 7 is a perspective view of the embodiment of FIG. 1; and,

FIG. 8 is a second perspective view of the embodiment of FIG. 1.

The features shown in broken lines do not form part of the claimed design.

1 Claim, 2 Drawing Sheets
